UNITED STATES PATENT OFFICE.

REGINALD HEBER DORSEY, OF BROOMES ISLAND, MARYLAND.

TOBACCO-PRESS.

1,260,162.

Specification of Letters Patent. Patented Mar. 19, 1918.

Application filed June 25, 1917. Serial No. 176,834.

To all whom it may concern:

Be it known that I, REGINALD HEBER DORSEY, a citizen of the United States, residing at Broomes Island, in the county of Calvert and State of Maryland, have invented certain new and useful Improvements in Tobacco-Presses; and I do declare the following to be a full, clear, and exact description of the invention, such as will enable others skilled in the art to which it appertains to make and use the same.

My invention relates to improvements in baling presses and more particularly tobacco presses and the primary object of the invention is to provide an improved form of a tobacco press in which a windlass and pulleys are used for increasing power in compressing and to secure a more efficient packing of the tobacco with a considerable saving of time and labor employed.

Another object of my invention is to provide a novel construction of frame and follower employed in the frame in which all parts of the mechanism are readily accessible and the bales or hogsheads employed may be more readily mounted and withdrawn from the frame than is capable of accomplishment, with the majority of these presses used at the present time. An additional object of the invention is to provide a novel and improved form of operating mechanism and connection for carrying out the compression of the tobacco and which construction is designed to produce the best results with the minimum of wear upon the parts.

With these different objects in view and with others which will appear from the description, my invention resides in the novel construction, combination and arrangement of parts to be more fully described and claimed taken in connection with the accompanying drawings which form a part of this specification.

Figure 1 is a side elevation of my improved press.

Fig. 2 is a longitudinal vertical section of same and Fig. 3 is a horizontal sectional view taken on line 3—3 of Fig. 1.

Fig. 4 is a transverse section on line 4—4 of Fig. 1, and Fig. 5 is a transverse section of line 5—5 of Fig. 1.

Fig. 6 is a perspective view illustrating the improved follower and bale frame and Fig. 7 is a vertical perspective view of the wheeled bale carrier employed.

In preparing tobacco for the market at

the present time, it is customary to compress the leaf tobacco in suitable hogsheads or bales by pressing down on a plunger. With this type of compressor it has been found difficult to obtain the required compression for shipping the largest amount of tobacco in the most compact package. It is with this object in view that I have designed the press to be hereinafter described with which it is possible to compress the tobacco contained in two hogsheads into the space of one hogshead at considerable saving of time and labor.

In the accompanying drawings similar reference characters designate corresponding parts throughout the several views. My improved press comprises a frame F consisting of a longitudinally disposed bottom beam 1 mounted on transversely extending end supporting beams 2 and a centrally disposed transverse beam 3. The top beam 4 is disposed in longitudinal and vertical alignment with the bottom beam 1 and spaced thereabove by an end member or beam 5 and the axle 6 of a windlass 7, mounted in the opposite end of the frame. Arranged intermediate the ends of the frame and secured at opposite sides of the side edges of the beams 1 and 4 is an aligned pair of side beams 8 disposed substantially intermediate the ends of the frame and adjacent the central supporting beam 3 in the windlass carrying end of frame.

Secured to the supporting beam 3 and the end beam 2 at the opposite end of the frame is a pair of track bars 9 extending longitudinally and in parallel spaced relations on the opposite sides of bottom beam 1 and in a horizontal plane therewith. The inner face of these track bars 9 adjacent the bottom beam 1 are faced with angle metal as designated at 10 to provide a suitable track to carry a wheeled carrier 11 adapted to support bales or hogsheads thereon.

Extending longitudinally in the frame is a pair of parallel vertically spaced arms 12 secured each at one end in any suitable manner rigidly between the side beams 8. These beams are spaced above the bottom of frame and extend to a point substantially midway of the adjacent end of frame as clearly illustrated in Figs. 1 and 2 mounted in a suitable manner on the inner end of arms 12 is a presser head 13, which in the present form is made circular to use upon hogsheads but which may be made to any

configuration desired depending upon the individual conditions existing at the time of use, as it can be made square and utilized for square bales and the like.

- 5 Disposed at the end of the frame in which the presser head 13 is located is a vertically positioned substantially rectangular follower plate 14 recessed at its upper and lower ends to receive the top and bottom 10 beams 1 and 4 for slidable engagement therewith. At the lower end of the plate, rollers 15 are suitably mounted to prevent friction between the follower and bottom beam 1 when the follower is moved thereon.
- 15 The projections at the lower end of the follower as designated at 16 are designed to be received in the spaces between the track bars 9 and the bottom beam 1 as clearly illustrated in Fig. 4. This construction will 20 serve to provide an efficient guide for the follower, and the rollers 15 will prevent any friction. On its inner face adjacent the presser head 13 the follower plate is provided with a similarly formed plunger 17 which may be suitably secured thereon in 25 any desired manner or formed integral therewith. Transversely arranged on the opposite side of the follower intermediate the ends thereof is a bar 18 secured thereto 30 and having its ends projecting beyond the side edges of the follower as illustrated in Figs. 4-6, and bifurcated at its ends to receive longitudinally extending bars 19, which in turn are received in the bifurcated 35 ends of a similarly formed bar 20 disposed between the arms 12 and in back of the presser head 13 for longitudinal movement between the arms. The bars 19 are detachably positioned in the ends of bars 18 and 20 40 by means of removable pins 21. This construction of the follower and bars provides a bale retaining frame and owing to the removable connection of the bars 19, comprising the sides of the frame, hogsheads or 45 bales may readily be placed on the carrier 11 or withdrawn therefrom.
- The carrier 11 is disposed between the follower 14 and presser head 13 and comprises longitudinally extending side members 22 50 having wheels 23 on the outer faces thereof and connected to transversely extending hogshead carrying braces 24. The end of the carrier adjacent the follower is provided with eyes 25, adapted to be engaged 55 by hook members 26 pivotally mounted on the follower as clearly illustrated in Figs. 6 and 7 so that when connected the carrier and follower will move in unison. Suitable straps or other retaining members 27 may 60 be disposed on the carrier as desired but preferably they are arranged and the carrier is designed to receive a pair of hogsheads 28 and 29 thereon which are disposed with their meeting ends open and with the 65 end plate 30 adjacent the presser head 13.

These hogsheads are first packed by hand and then applied to the carrier as illustrated in Figs. 1 and 2 so that when compressed the leaf tobacco generally indicated as at 31 will be compressed into the space occupied 70 by one hogshead as indicated in Fig. 3.

Disposed between the arms 12 on a pivot bolt 32 extending between the side beams 8 is a multiple sheaved pulley 33 and mounted in an eye bolt 34 secured on the bar 20 75 at its center is a second multiple sheaved pulley 35. Disposed in a well known manner over these pulleys is a cable 36 connected at the windlass carrying end of the frame to a stud 37 on the windlass. The bar 20 80 will move between the bars 12 and when the windlass is actuated through the handle 38 the follower will be drawn up against the presser head 13 compressing the tobacco into the hogshead adjacent the follower 85 until the limit of compression has been reached. A suitable ratchet mechanism indicated at 39 is provided to retain the compression and prevent retrograde movement of the follower. If desired a suitable brace 90 (not shown) may be employed between the end of the frame and the follower to prevent retrograde movement. When compressed and held against retrograde movement the side bars 19 may be removed and 95 the hogshead 28 slid over the arms 12 and a suitable retainer ring (not shown) fastened in the hogshead to retain the plate 30 therein. When finished compression may be relieved and the hogshead withdrawn from 100 the carrier.

To provide an efficient means for return movement of the follower and carrier I have provided a cable 40 adapted for connection at one end to a stud 41 on the windlass and 105 passing over a pulley 42 secured on the end beam 5 through a suitable notch provided in the follower and end beam and secured in an eye 43 on rear face of follower, so that when the ratchet 39 is disengaged and the 110 windlass reversed the cable 40 will draw the follower and carrier in the opposite direction and return the parts to normal position.

I claim:

1. A baling press as described comprising a frame, a presser head therein, intermediate its ends and spaced above the bottom thereof, operating mechanism in one end of said frame, a follower slidable longitudinally in 120 said frame at the other end, a carrier in said frame between the head and follower, members on said follower to retain a bale between said head and follower, a draw bar on said members, connection between said draw member and operating mechanism, a power increasing device carried by said presser head and connection between said carrier and follower.

2. In a baling press a frame comprising 130

- horizontally disposed top and bottom beams, and end beam, a windlass in one end, side beams intermediate the ends of said frame, a pair of vertical spaced parallel, longitudinally extending arms, secured between said side beams by one end and above the bottom of frame, a presser head secured to the outer ends of said arms, a bale carrier between said head and follower, multiple sheaved pulleys mounted between said longitudinally extending arms and cable connection between said follower and windlass over said pulleys. 3. In a baling press, a horizontally disposed frame, a windlass in one end thereof, a follower slidable longitudinally in said frame, a pair of vertical spaced, parallel, longitudinally extending arms, secured rigidly at one end in said frame intermediate the ends thereof, a presser head on the ends of said arms, a wheeled carrier in said frame between the follower and presser head, connection between said carrier and follower, a bale retaining frame on the follower, a draw bar member on said frame and disposed between the presser head and arms, cable connection between said windlass and draw bar member and power increasing pulleys therefor between said arms. 4. In a baling press, a frame, a stationary presser head intermediate its ends, a follower in one end of said frame and a windlass in connection therewith in the other, a bale retaining frame carried by said follower, the sides of said frames being detachable for inserting and removing bales and a bale carrier in connection with said follower for supporting said bales between said follower and presser head. 5. A baling press as described including a horizontally disposed frame, having alined top and bottom beams, an end beam, vertically disposed side beams intermediate the ends of said frame, a windlass in the opposite end of said frame, a presser head rigidly secured between said beams, a follower in guiding engagement with said top and bottom beams, a carrier movable longitudinally in said frames between said head and follower and connection between said windlass 50 and follower. 6. In a baling press, a frame, comprising horizontally disposed top and bottom beams, an end beam, a windlass mounted in the opposite end of said frame, side beams intermediate the ends thereof, a presser head mounted between said side beams, a track in said frame, a wheeled bale carrier thereon, a substantially rectangular follower recessed at its ends to slidably engage said top and bottom beams, connection between said follower and carrier pulleys mounted on said presser head and connecting cable between said windlass and follower over said pulleys. 7. In a baling press, a frame, top and bottom beams therefor in longitudinally vertical alinement, oppositely arranged side beams secured to said top and bottom beams intermediate the ends thereof, a windlass at one end, a pair of track members, spaced horizontally from the opposite sides of said bottom beam and in a horizontal plane therewith and extending between said side beams, a substantially rectangular follower recessed at its ends to receive said top and bottom beams and slide thereover, rollers carried by said follower, a wheeled bale supporting carrier on said track and connected to said follower, and connection between said windlass 60 and follower at both sides thereof for reciprocation of said follower. 8. In testimony whereof I have hereunto set my hand in the presence of two subscribing witnesses.
